(57) CLAIM

The ornamental design for pants, as shown and described.

DESCRIPTION

FIG. 1 is a top left perspective view of the pants of the present invention;

FIG. 2 is a front view thereof;

FIG. 3 is a partial enlarged view taken along lines 3-3 of FIG. 2;

FIG. 4 is a right side view thereof;

FIG. 5 is a left side view thereof;

FIG. 6 is a rear view thereof;

FIG. 7 is a top view thereof; and,

FIG. 8 is a bottom view thereof.

The broken lines represent portions of the pants that form no part of the claimed design.
